Design - Top rail of Room.
Mr. C. C. Grinnell
John C. Grinnell
1862

George Crompton, of Worcester, Mass.
Letters Patent No. 1562, dated April 8, 1862.

The schedule referred to in these Letters Patent and making part of the same.

To all whom it may concern:

Be it known that I, George Crompton of Worcester,
State of Massachusetts, have made a certain new and original design for the

top rail of looms for weaving, of which the following is a full, clear, and exact description, reference being had to the annexed drawings, making part of this specification, of which—

Fig. 1. is a side elevation of a loom with my ornamental top rail applied.

Fig. 3. is a front elevation and figure 2. a section taken at a. b. Fig. 3.

In looms for plain weaving, where canes are used for making the shed, a simple, light top rail, made of wood or iron is required. For this purpose, I have made a design which I will now proceed to describe.

C. C. are two upright standards either cast or bolted to iron sides d. d. on the line b. m. The legs of these uprights merge into and finally terminate in a narrow neck. To the top of these standards is bolted a top rail v. by bolts b. b. passing through the feet of the rail and the side standards d. d. The rail rises from each standard in a curved line commencing the width of the same standards and the breadth of the neck or top of the standard at the point j. j. to the points v. v. the inner or lower part being a flat rib extending the entire length of the rail k. k. k. k. the upper part is a vertical rib, slightly increasing in depth until reaching the points v. v. This gentle rise and curve continues until reaching the centre shown by the vertical red line at a. b. Between the two points v. v. the stock is removed, forming a panel on both sides of the rail, leaving the lower (K) a wide, and the top (n) a narrow rib as seen by section at Fig. 2. taken at a. b. Figure 3. Thus forming a light, strong, and elegant rail.

What I claim as new and desire to secure by Letters Patent, is the configuration and ornamental design of top rail for looms as herein shown.

W. H. Smith.
